US0D1038788S

(12) **United States Design Patent** (10) Patent No.: **US D1,038,788 S**
(45) Date of Patent: ** Aug. 13, 2024

(54) **SENSOR ASSEMBLY**(71) Applicant: **INFORMED DATA SYSTEMS INC.**,
New York, NY (US)(72) Inventors: **Matthew Chapman**, Oakland, CA
(US); **Steven Portela**, San Francisco,
CA (US); **Ashwin Pushpala**, San
Francisco, CA (US); **Mark Prommel**,
Montclair, NJ (US); **Pil Ho Chung**,
Palisades Park, NJ (US)(73) Assignee: **ONE HEALTH BIOSENSING INC.**,
New York, NY (US)(**) Term: **15 Years**(21) Appl. No.: **29/891,202**(22) Filed: **May 2, 2023**

CLAIM

The ornamental design for a sensor assembly, as shown and described.

DESCRIPTION

FIG. 1 is a top perspective view of a sensor pod of a sensor assembly showing the new design in accordance with another embodiment.

FIG. 2 is a left side view of the sensor pod in FIG. 1.

FIG. 3 is a right side view of the sensor pod in FIG. 1.

FIG. 4 is a back view of the sensor pod in FIG. 1.

FIG. 5 is a front view of the sensor pod in FIG. 1.

FIG. 6 is a top view of the sensor pod in FIG. 1; and,

FIG. 7 is a bottom view of the sensor pod in FIG. 1; and, FIG. 8 is a bottom perspective view of the sensor pod in FIG. 1.

The details shown in broken lines illustrate portions of a sensor pod that form no part of the claimed design. The dash-dot-dash broken lines illustrate the boundaries of the sensor pod and form no part of the claimed design.
